HACKSAW HANDLE

Raymond C. Dreier, 7311 East End Ave., Chicago, Ill.

Filed Jan. 18, 1962, Ser. No. 68,357

Term of patent 14 years

(Cl. D93—4)

FIG. 1 is an elevational view of one side of a hacksaw handle embodying my new design, other portions of a complete hacksaw being additionally shown in broken lines for illustrative purposes only;

FIG. 2 is an elevational view of the other side of the hacksaw handle;

FIG. 3 is an end view of the handle, as seen from the left of FIG. 1;

FIG. 4 is a view of the opposite end of the handle, as seen from the right of FIG. 1;

FIG. 5 is a bottom view of the handle;

FIG. 6 is a fragmentary cross-sectional view taken substantially along the line 6-6 in FIG. 1; and

FIG. 7 is a cross-sectional view taken substantially along the line 7-7 in FIG. 1.

I claim:

The ornamental design for a hacksaw handle, substantially as shown.
